UNITED STATES PATENT OFFICE.

GEORGE W. WEBER, OF NEW YORK, N. Y., ASSIGNOR TO AMERICAN CAN COMPANY, OF NEW YORK, N. Y., A CORPORATION OF NEW JERSEY.

PAINT-CAN.

No. 830,122.

Specification of Letters Patent.

Patented Sept. 4, 1906.

Application filed May 22, 1905. Serial No. 261,510.

To all whom it may concern:

Be it known that I, GEORGE W. WEBER, a citizen of the United States, residing in New York, in the county of New York and State 5 of New York, have invented a new and useful Improvement in Paint-Cans, of which the following is a specification.

My invention relates to improvements in paint-cans.

10 My invention consists in a can for holding paints or other materials provided at one end with a friction-top and friction-cap closure for the liquid-receptacle of the can, so that the same can be readily and repeatedly 15 opened and closed, as required, and provided at its other end with a deep countersunk head seamed to the body of the can and forming a secondary receptacle or chamber for receiving bronze-powder or other mate- 20 rial and closed by a thin soft-tin or sheet-metal supplemental head crimped or seamed to the body and adapted to be readily cut out, so that the dry or powder paint mate- 25 rial employed may be kept separate from the liquid paint material until the paint is desired to be used, when by first simply cutting out the soft-tin head the bronze-powder or other dry material may be taken out and then mixed with the liquid material in the 30 can, the friction-cap being of course first removed.

35 My invention also consists in the novel construction of parts and devices and in the novel combinations of parts and devices herein shown and described.

In the accompanying drawings, forming a part of this specification, Figure 1 is a top or plan view of a can embodying my invention. Fig. 2 is a central vertical longitudinal sec- 40 tion, and Fig. 3 is a cross-section on line 3 3 of Fig. 2.

45 In the drawings, A represents a sheet-metal can-body; B, the friction-top of the can, having an external flange b, soldered or other- wise united to the can-body A, and a down- 50 wardly-projecting flange b', surrounding the large opening B' in the friction-top of the can.

55 C is the friction-cap, having the custom- ary depending flange or wall c in tight frictional engagement with the corresponding flange b' of the friction-top B, so as to form a liquid-tight closure. The friction-cap C has a marginal rim or flange c' and a fold c² to

strengthen and stiffen the friction-cap and 55 serve as a shoulder for prying it off in opening the cans in the customary way. The bottom head D of the can is furnished with a deep countersink or wall d, which is united by a downwardly folded or crimped seam d' 60 with the lower end of the can-body A, thus forming an external shoulder or bead at the lower end of the can-body. The deep countersink or flange d of the can-head forms a 65 supplemental receptacle or chamber D' for containing bronze-powder or other dry paint material. This secondary chamber or receptacle D' is closed by a soft or taggers tin sheet-metal supplemental head or cover F, having a flange f crimped or otherwise 70 seamed or united to the can-body, and thus closing the bronze-receptacle D'. The seam uniting the flange d of the countersunk head D of the can with the can-body may prefer- 75 ably be also soldered to insure that this joint is perfectly liquid-tight.

The liquid paint or material X is placed in the main receptacle or chamber A' of the can, which is closed by the friction-cap C. The bronze or other dry paint material X' is 80 placed in the supplemental chamber D'. Both chambers A' and D' of the can are adapted to be readily opened, the main chamber A' by simply prying off the friction cap or cover in the customary manner and 85 the supplemental chamber D' by cutting out the soft-tin supplemental head F of the can. After the supplemental soft head F' is cut out and the bronze-powder or other material in the chamber D' removed the can is then 90 used as any ordinary friction-top paint-can. By my improved can the liquid paint mate- 95 rial and the dry or powder paint material may be kept and shipped separate and in proper proportions for mixing together when the contents of the can are desired to be used. This prevents all deterioration of the paint, such as ordinarily occurs where the bronze- 100 powder and liquid paint are mixed together and sealed up together in the paint-factory. My improved can, it will thus be seen, has two separate chambers or receptacles each adapted to be readily opened, one, the liquid-chamber, by the friction-top and friction- 105 cap closure at the upper end of the can-body, and the other, the bronze-powder or supple- mental material-chamber, being adapted to be readily opened and closed by the soft or

severable sheet-metal head F at this end of the can-body. The intermediate or countersunk head D thus divides the can into two separate chambers, so that two different materials may be contained in one and the same can and kept separate from each other until required for use, when they may be readily mixed together.

I claim—

- 10 1. A paint-can having at one end of its body a top with an opening therein and a cap for opening and closing the same, and at the other end of its body a deep countersunk head seamed thereto, and a supplemental soft-tin or severable sheet-metal head seamed or crimped to the can-body and closing the supplemental chamber formed by the deep countersink of said bottom head.
- 15 2. A can provided at one end of its body with a top with an opening therein and a cap for opening and closing the same, and furnished at its other end with a thin or severable sheet-metal head and an intermediate head dividing the can into two chambers, substantially as specified.
- 20 3. A can having a readily-opening closure at one end, a soft or severable metal head at its opposite end, and an intermediate head
- 25

dividing the can into two chambers or receptacles, substantially as specified.

4. A can provided with a top with an opening therein and a cap-closure therefor at one end, a soft or severable sheet-metal head at its opposite end, and a deep countersunk intermediate head dividing the can into two chambers or receptacles and having a cylindrical wall fitting snugly within the can-body, substantially as specified.

5. A can provided with a top with an opening therein and a cap-closure therefor at one end, a soft or severable sheet-metal head at its opposite end, and a deep countersunk intermediate head dividing the can into two chambers or receptacles, said deep countersunk intermediate head having an externally-folded seam uniting it to the can-body to form an external shoulder on the can-body, and said soft or severable metal head having a seam-flange crimped about said external shoulder on the can-body to unite the same thereto, substantially as specified.

GEORGE W. WEBER.
